(57) **CLAIM**

The ornamental design for a resurfacing tool for a yaw disc brake, as shown and described.

DESCRIPTION

FIG. 1 is a front perspective view of a resurfacing tool for a yaw brake disc, showing out new design;

FIG. 2 is a rear perspective view thereof;

FIG. 3 is a right side view thereof;

FIG. 4 is a left side view thereof;

FIG. 5 is a top view thereof;

FIG. 6 is a bottom view thereof;

FIG. 7 is a rear view thereof; and,

FIG. 8 is a front view thereof.

The broken lines in the drawings illustrate portions of the resurfacing tool for a yaw brake disc that form no part of the claimed design.
